Primary Examiner — Jennifer L Rempfer*Assistant Examiner* — Danielle Nichole Bowly(74) *Attorney, Agent, or Firm* — McGinn I.P. Law Group, PLLC.(57) **CLAIM**

The ornamental design for printer, as shown and described.

DESCRIPTION

FIG. 1 is a perspective view of a printer showing my new design;
 FIG. 2 is another perspective view of the printer;

FIG. 3 is a front view of the printer;

FIG. 4 is a rear view of the printer;

FIG. 5 is a right side view of the printer;

FIG. 6 is a left side view of the printer;

FIG. 7 is a plan view of the printer; and,

FIG. 8 is a bottom view of the printer.

The broken lines in the drawings depict portions of the printer that form no part of the claimed design.

1 Claim, 8 Drawing Sheets(56)
